WRIST WATCH STRAP CONSTRUCTION

Willard A. Davis, Providence, R. I., assignor to
 S. & B. Lederer Company, a corporation of
 Rhode Island

Application June 7, 1937, Serial No. 146,702

2 Claims. (Cl. 224—4)

My present invention relates to the jewelry art, and has particular reference to a novel construction for bracelets and wrist watch straps.

It is the principal object of my invention to provide a strap having a small number of parts, which may be readily manufactured at a low cost.

It is a further object of my invention to provide a strap having its parts resilient to engage the wrist for retaining the strap thereon.

It is an additional object of my invention to provide a strap having firm support for the wrist watch.

With the above and other objects and advantageous features in view, my invention consists of a novel arrangement of parts more fully disclosed in the detailed description following, in conjunction with the accompanying drawing, and more specifically defined in the claims appended thereto.

In the drawing, Fig. 1 is a plan view of the novel strap;

Fig. 2 is an extended view thereof, parts being broken away;

Fig. 3 is a section on the line 3—3 of Fig. 2;

Fig. 4 is a view of the assembled wire support;

Fig. 5 is a view of the shaped wire prior to assembly; and

Fig. 6 is a view similar to Fig. 2, but showing a modified construction.

Referring to the drawing, the wrist watch strap includes a novel support 11, see Fig. 5, which is formed of a single piece of resilient wire 12, initially bent into an elongated generally elliptical shape; a plate 13 is preferably stamped of sheet metal and its edges 14 are turned over the center parts of the wire, as disclosed in Fig. 4, to securely lock the free ends of the wire 12 together, and to serve as a support for the wrist watch, as hereinafter explained. A covering 15

of leather or other flexible material, see Fig. 2, is then sewed around the assembled wire support 11 to form a sheath, and retaining ears 16, which are preferably of leather, but may be of metal, are secured to the upper portion of

the sheath, for receiving the bails of a wrist watch. The ends 17, 18 of the strap are then bent into an arcuate form as disclosed in Fig. 1, thus completing the construction of the novel wrist watch strap.

The above described construction has many advantages over other types of wrist watch straps, as the parts required for manufacture comprise a simple wire form and a sheet metal plate which are assembled together to form a

support, thus eliminating any need for solder or other joining construction, the parts then being covered by leather or the like, which is sewed around the assembled support and is provided with suitable means for the mounting of a wrist watch. The entire manufacturing procedure is thus very simple in nature, and the cost of manufacture is extremely low; the completed wrist watch strap is resilient, because of the wire form 11, whereby it hugs the wrist, the ends 17 and 18 are readily separable to permit removal of the strap from the wrist and mounting of the strap thereon, and the plate 13, which is embedded in the leather sheath, serves as a very firm support for the wrist watch, and as a spacer element to prevent the sides of the wire from moving inwardly towards each other, wherefore no additional sewing or other means is required for maintaining the wire form in its proper position within the sheath.

Although the above described construction is preferred, it may be advisable, for certain uses, to provide a positive closure for the ends of the wrist watch strap. A wrist watch strap such as indicated at 19 in Fig. 6 may therefore be utilized, in which the ends of the sheath are respectively extended to provide a tongue 20 at one end having openings 21, and a buckle end 22 at the other end having a buckle 23 mounted thereon in the usual manner and provided with a buckle pin 24, whereby the strap ends may be buckled together. The construction of the wire support, and the mounting therein in its sheath, are similar to the construction previously described.

While I have described specific constructional embodiments of my invention, it is obvious that changes in the shape, size, and material of the parts and in the manner of assembly of the parts, may be made to suit the requirements for different wrist watch strap or bracelet designs, without departing from the spirit and the scope of the invention as defined in the appended claims.

I claim:

1. A wrist watch strap comprising a one piece elongated wire frame having its free ends in contiguous relation adjacent the center thereof, a metallic support plate having its edges rolled to engage the sides of the wire frame and to lock said free ends, and a covering of flexible material for said frame and said plate.

2. A wrist watch strap of generally circular form comprising a one-piece elongated wire frame having its free ends in contiguous rela-

tion adjacent the center thereof, a sheet metal plate locked to said frame at the central portion thereof and adapted to engage the sides of said wire frame and to lock said free ends, and a covering of flexible material for said frame and spacing element, one end of said

flexible material being extended beyond the frame to form an integral strap closure tongue, the other end of said flexible material having a buckle.
